UNITED STATES PATENT OFFICE.

THEODORE HUDDNUT, OF TERRE HAUTE, INDIANA.

HOMINY-MILL.

SPECIFICATION forming part of Letters Patent No. 295,554, dated March 25, 1884.

Application filed October 17, 1883. (No model.)

To all whom it may concern:

Be it known that I, THEODORE HUDDNUT, a resident of Terre Haute, Vigo county, Indiana, have made certain new and useful Improvements in Hominy-Mills, a description of which is set forth in the following specification, reference being made to the accompanying drawings, in the several figures of which like letters indicate like parts.

10 My invention relates to the construction of cylinders for hominy-mills, and the means for securing these blades to the cylinders, and will be understood from the following description.

15 In the drawings, Figure 1 represents a side view of the cylinder, with the blades in place on the upper and lower plates, the blades being left off the plate in front so as not to confuse the view. Fig. 2 represents a longitudinal section of the same. Fig. 3 represents a cross-section on the line $x-x$, Fig. 1. Fig. 4 is a front view of one of the blades, with the open slot vertical; and Fig. 5 represents a front view of one of the blades, with 25 the open slot in a horizontal position.

C is a wooden cylinder with four squared sides, to each of which the iron plate p , having projections or lugs l , is attached by screws or bolts. The corners of the cylinder are 30 dressed off, as shown in Fig. 3, and the flat surfaces thus formed are covered for the purpose of balancing the cylinder, by beveled plates bp ; or pieces of metal f are inserted for the purpose, as shown in Fig. 3, where two 35 of the corners are covered by the plates bp and two are filled with metal, the result in either case being similar—viz., the wooden cylinder at these points is balanced or weighted, so that it will run true while in operation.

40 Through the length of this wooden cylinder C runs the iron axis or shaft a , squared in the wood, but turned round at either end for journals. The plates p have lugs l projecting outward at regular intervals of distance through 45 holes, in which a threaded rod, sr , is passed loosely, this rod being long enough to pass through all the lugs. This rod is threaded to receive set-nuts n , one of which is set at either end of each of the lugs l and works against a 50 washer or loose plate, wp . Between this

washer-plate and the end of the lug the tooth or blade b is set, the open slot allowing the blade to pass the rod sr until the latter rests against the rounded end of the slot. This slot may be cut in the blade either vertically 55 or horizontally, as shown in Figs. 4 and 5. When the blade is fixed in place, the nut n is tightened upon the rod sr against the plate wp , and the tooth is held firmly in position for work. If the tooth becomes dull or broken, 60 by loosening the nut, it may easily be removed without disturbing any one of the others, and in this respect my device has a great advantage over machines whose blades cannot be separately removed. Again, the form of the 65 blades b is a great improvement over those having a narrow shank, for at these narrow places the blade is almost sure to break, while my blade is of uniform width throughout and of uniform strength. The slight curve of the 70 cutting-edge of my blade is better than a shorter curve, for the latter wears away more rapidly and sooner comes to a point, and is rendered useless. The figures 1, 2, 3, and 4 upon the cylinder in Fig. 1 serve to indicate 75 the relative points where the blades are placed on the four sides, these points being so relatively spaced that between each pair of lugs on the same plate the spiral around the cylinder is broken, and this prevents the crowding 80 and packing of the grain at one end of the cylinder. This always occurs where the continuous spiral is not broken, and the result is that very soon the cylinder is so tightly packed that the belt will fly off, the cylinder 85 stopped or burst.

The devices here shown and described are improvements upon those shown in Reissued Letters Patent No. 10,057, granted me on the 7th day of March, 1882.

90 Of course it will be understood by all those familiar with the art of constructing or operating hominy-mills that the devices here shown and described are placed inside a hollow casing, having an opening into which the grain 95 is poured; but this casing is no part of my new invention, and therefore need not be here described.

What I claim, and desire to secure by Letters Patent, is the following:

1. The wooden cylinder C, having square sides and mounted on axis *a*, the metal plates *p*, adapted to be secured to the squared sides of the cylinder, and provided with lugs *l*, integral with the plates, and set at such distances apart as to break a continuous spiral from one end of the cylinder to the other, all combined substantially as described.

2. The wooden cylinder C, having squared sides and mounted on axis *a*, the metal plates *p*, provided with lugs *l*, integral with the plates, adapted to be secured to the sides of the cylinder, and balancing devices secured at the corners of the cylinder, all combined substantially as described.

3. The plate *p* with lugs *l*, adapted to receive the rod *sr*, in combination with such rod and set-nuts *n*, substantially as described.

4. The plate *p* with lugs *l*, adapted to re-

ceive the rod *sr*, in combination with such rod, the set-nuts *n*, washer-plates *wp*, and blades *b*, substantially as described.

5. The cylinder C, mounted on axis *a*, the plates *p*, having lugs *l*, the rods *sr*, set-nuts *n*, and blades *b*, all combined substantially as described.

6. The cylinder C, mounted on axis *a*, having plates *p*, provided with lugs *l*, the rods *sr*, passing through said lugs, the set-nuts *n*, washer-plates *wp*, and blades *b*, with open 30 slots, all combined substantially as described.

In witness whereof I have hereto set my hand this 12th day of October, A. D. 1883.

THEODORE HUDNUT.
